GEORGE W. BUDDE AND CHARLES H. BUDDE, OF ST. LOUIS, MISSOURI.

AQUATIC TOY.

1,318,049.

Specification of Letters Patent.

Patented Oct. 7, 1919.

Application filed February 3, 1919. Serial No. 274,598.

To all whom it may concern:

Be it known that we, GEORGE W. BUDDE and CHARLES H. BUDDE, citizens of the United States, residing in the city of St. Louis and State of Missouri, have invented new and useful Improvements in Aquatic Toys, of which the following is a specification.

This invention has for its general object 10 to provide a novel aquatic toy which by the alternate occlusion and escape of air carried under pressure by the device will cause the same alternately to rise to the surface and sink to the bottom of a body of water.

15 The invention finds its most attractive embodiment in a toy submarine boat, and such embodiment is illustrated in the accompanying drawing; but the invention may equally well be embodied in other devices, such, for example, as toy divers, fish, animals, and the like.

In the accompanying drawing:

Figure 1 is a longitudinal sectional view of a toy submarine provided with our invention and lying at, or near the surface of the water;

Fig. 2 is a similar view showing the submarine in the position it assumes as it starts to submerge;

30 Fig. 3 is a section on the line 3—3 of Fig. 1; and

Fig. 4 is a broken sectional view of the upper portion of the device showing a modification.

35 Referring now to the drawing the numeral 1 indicates a cylinder which may be made of any thin sheet metal such as tin.

At any suitable point this cylinder is provided with an air valve 2 to which an ordinary bicycle pump may be attached for the purpose of filling the cylinder 1 with compressed air. On its upper side near one end the cylinder 1 has secured therein a tube 3 having a small orifice 4 for the escape 40 of air. Secured at a suitable distance above the top of the cylinder 1 by means of metal plates 5, 6 located, respectively, at the sides and forward ends thereof, according to the construction shown in Figs. 1 and 2, is an air trap 7 which is in the shape of an elongated inverted trough, rectangular in cross-section, as shown by Fig. 3, and of gradually decreasing depth from the forward to the rear end thereof, as indicated in Figs. 1 and 2. The air trap 7 is so positioned 45 that the lower edges of its side walls 8 are

parallel with the top of the cylinder 1 while the top 9 inclines downwardly from the front to the rear of the trap. As shown in Fig. 3, the trough is opened on its under side throughout its length and at its rear end, but it is closed at the forward end as indicated at 10. To maintain the device in an upright position we support from hangers 11 pending from the cylinder 1 near the ends thereof, a keel 12, which is merely a strip of metal, or other substance, for weighting the bottom of the cylinder 1. It is not necessary that the keel, or weight 12 should be supported below the tank 1, as 50 the bottom of said tank itself can be weighted, or, in the case of the device shown in the drawing, the bottom or keel of the vessel itself could be weighted. In applying our invention to a tin submarine the cylinder 1 is mounted in the upper portion of a hull 13 and the cylinder has mounted near its forward end an imitation periscope 14 which, however, does not communicate with the interior of the cylinder 1, the latter being 55 air tight except for the opening controlled by the valve 2, and the orifice 4 for the escape of air.

In the operation of the device shown in Figs. 1 and 2, the cylinder 1 is filled with 60 compressed air by means of a bicycle pump, or the like, attached to the valve 2, and it is then placed in the water contained, for example, in a wash tub, bath tub, fountain, or aquarium. The weight of the device will 65 cause it to sink slowly to the bottom. As air escapes from the orifice 4, the bubbles formed will congregate in the forward part of the trap 7, and will, after a little while, cause the boat to rise, so that the periscope 70 14 will project above the surface of the water and the trap 7 will lie on, or slightly above the surface. As the escape of air continues, the bubbles will be forced toward the rear of the trap 7 by the pressure 75 formed by successive bubbles of air and as they move to the rear end of said trap they will cause said rear end to be elevated, as shown by Fig. 2, thus allowing all of the air occluded by the trap to escape, the buoyancy 80 of the device will thus be destroyed, and it will again sink beneath the water. A device slightly larger than that shown in the drawing and made by us has in actual practice continued to alternately rise and 85 submerge over a period varying from six to eight hours with one charge of air.

In the modification shown in Fig. 4, the trap 7 is pivotally mounted at its forward end in the upper ends of standards 15 by means of pivot pins 16, or in any other preferred manner, the forward end being supported a slight distance above the top of the cylinder 1 and the rear end resting on the top of said cylinder. The operation with this modified construction is substantially the same as described above, except that when the air bubbles collect under the trap 7 the rear end of the latter will in time be raised, the trap, as a whole, turning on the pivots 16 and permitting the bubbles to escape. In this operation the bottom edge of the forward end will engage the top of the cylinder 1 and limit the upward movement of the rear end of the trap.

This modified construction has some advantages over the rigid form of air trap shown in Figs. 1 and 2, in that it does not require such a nice adjustment of the parts to secure the desired operation, admits of a wider range of adjustment as to the periods between the rise and sinking of the device, and operates to produce a somewhat more sharply-defined or positive movement, in causing the device to submerge, than does the rigid trap.

By varying the size of the orifice 4 the rapidity with which the device will operate may be correspondingly varied. That is to say, the larger the opening the more rapidly the device will operate. Variations in this regard can also be produced by changing the length of the air trap, especially in the hinged type of the latter. It will be obvious that changes in the form, construction and arrangement of the parts shown will be made according to the character of the device to which our invention is applied, and that such changes may be made without departing from the principle of our invention, which may be defined as comprising a hollow body capable of being filled with compressed air and provided with an orifice for the escape of air, and a trap located above the upper surface of the body for permitting bubbles of escaped air to collect thereunder to elevate said body, and, as the bubbles are forced to the rear of the trap by pressure, causing the trap to be upturned to permit the bubbles to escape, thus destroying the buoyancy of the body and allowing it to submerge.

We claim:

1. An aquatic toy comprising a hollow body capable of containing compressed air and having an escape orifice adapted to be normally submerged in a body of water containing the toy and an air trap carried by said body above said orifice and provided with an air escape at a distance from said orifice, whereby said toy will be caused to rise by occlusion of escaped air beneath said

trap, and to submerge by the escape of the air from said trap, in alternation.

2. An aquatic toy comprising a hollow body capable of containing compressed air and having an escape orifice adapted to be normally submerged in a body of water containing the toy, and an elongated trap mounted on the upper side of said body and above said orifice, whereby said toy will be caused to rise by occlusion of escaped air beneath said trap and to submerge by the escape of the air from said trap, in alternation.

3. An aquatic toy comprising a hollow body capable of containing compressed air and having an escape orifice adapted to be normally submerged in a body of water containing the toy, and an elongated member in the shape of an inverted trough located above said orifice and at a distance from said body and having one end adjacent to said orifice closed and an end farther removed therefrom open, whereby said toy will be caused to rise by occlusion of escaped air beneath said trap and to submerge by the escape of the air from the open end of said trap, in alternation.

4. An aquatic toy comprising a hollow body capable of containing compressed air and having an escape orifice in its upper side adapted to be normally submerged in a body of water containing the toy, an elongated member in the form of an inverted trough secured to said body and over said orifice, one end of said member adjacent said orifice being closed and its opposite end farther removed therefrom being open, said trough inclining downwardly from its closed end to its open end, whereby said toy will be caused to rise by occlusion of escaped air beneath the portion of said member adjacent the closed end and to submerge by the escape of the air from the open end of said member, in alternation.

5. An aquatic toy comprising a hollow body capable of containing compressed air and provided on its upper side with an escape orifice adapted to be normally submerged in a body of water containing the toy, an inverted trough-shaped member secured to said body above said orifice and having its interior accessible to the water, said member having an end adjacent said orifice closed and an end farther removed therefrom open, whereby said toy will be caused to rise by occlusion of escaped air beneath said member and to submerge by the escape of air from the open end of said member, in alternation.

6. An aquatic toy comprising a hollow member capable of containing compressed air, and having an escape orifice adapted to be normally submerged in a body of water containing the toy, an elongated member in the shape of an inverted trough secured to

said body and located above said orifice and accessible to the water, said member having an end adjacent to said orifice closed and an end farther removed therefrom open where-
5 by said toy will be caused to rise by occlusion of escaped air beneath said member, and to submerge by the escape of the air from the open end thereof, in alternation.

7. An aquatic toy according to claim 6,
10 in which the elongated member is pivotally mounted at its forward end on the hollow member.

8. An aquatic toy comprising a hollow body capable of containing compressed air
15 and having an escape orifice adapted to be normally submerged in a body of water containing the toy, and an elongated trap pivotally mounted at one end on the upper side of said body and above said orifice, whereby
20 said toy will be caused to rise by occlusion of escaped air beneath said trap and to sub-

merge by the lifting of said trap by pressure of the occluded air to permit the escape of said air, in alternation.

9. An aquatic toy comprising a hollow body capable of containing compressed air and provided with a valved-opening for charging it, and with an escape orifice adapted to be normally submerged in a body of water containing the toy and an air trap 25 carried by said body above said orifice and provided with an air escape at a distance from said orifice, whereby said toy will be caused to rise by occlusion of escaped air beneath said trap, and to submerge by the 30 escape of the air from said trap, in alternation.

In testimony whereof, we have hereunto set our hands.

GEORGE W. BUDDE.
CHARLES H. BUDDE.
